Attorneys.

UNITED STATES PATENT OFFICE.

JOHN SQUIRES, OF DETROIT, MICHIGAN, ASSIGNOR TO ECONOMIES RESEARCH COMPANY, OF HAVANA, ILLINOIS, A CORPORATION OF ILLINOIS.

OIL BURNER.

Application filed June 10, 1924. Serial No. 719,046.

To all whom it may concern:

Be it known that JOHN SQUIRES, a citizen of the United States of America, residing at Detroit, in the county of Wayne and State of Michigan, has invented certain new and useful Improvements in Oil Burners, of which the following is a specification.

My invention relates to oil burners and more particularly to the so-called domestic oil burners.

The object of my invention is in the provision of an oil burner of the vertical shaft rotary cup type having a motor adjustably related thereto, in a manner to control the speed of rotation thereof.

Another object of my invention is in the provision of an oil burner having means for relating the atomizing portion and the power connection in an adjustable relation for controlling the speed of the atomizer.

A further object of my invention is in the provision of an adjustable means for relating a fuel atomizing portion and a power connection for the purpose of controlling the speed of the atomizer to more efficiently burn the various grades of oil.

Further objects of my invention will appear in the following specification taken in connection with the annexed drawings in which:

Figure 1 is a partial cross sectional view of my vertical shaft burner.

Figure 2 is a plan view of the device with the atomizing cup removed.

Referring to the drawings in Figure 1, I have shown an oil burner of the domestic type, said burner being generally referred to as the vertical shaft rotary cup type.

Generally, it may be said that this burner is adapted for house installation and is placed within the combustion chamber of the conventional furnace. The entire structure is located within the combustion chamber with the exception of fuel pipes, gas pipes and electrical connections thereto. Located within the combustion chamber at a desirable height above the floor is the hearth 10, said hearth being located by any desirable means to adjacent portions or rather convenient portions on the inside of the furnace. This hearth 10 is made of a substance not readily affected by intense heat and has a glazed surface impervious to the fuel used by the burner. No particular means for supporting the hearth within the combustion chamber of

the furnace is shown inasmuch as this structure would vary for the different types of furnaces. Similarly no combustion chamber is shown although the hearth therefor has been disclosed as 10. The burner itself projects, or rather the atomizing portion thereof, through an aperture of considerable size in the hearth 10 as clearly shown in Figure 1. A base 11 rests upon the floor of the furnace and upon this base is mounted a casing 12 which houses the power plant of the burner. The base 11 has a leveling means thereon. This housing 12, prevents the accumulation of dirt, oil, etc., upon the electric motor 13 which supplies the power to the atomizing portion to be described. The electric motor 13 is supported by the plate 14 and bracket 15 which are integral, and are adjustably related to the base 11 as a unit by an adjustable screw member 16. The above adjustable means permits a longitudinal movement of the motor and portions in connection therewith, when desired. The axis 17 of the motor 13 has a flexible connection 18 with a stub shaft 19 and a fuel pump 20 is mounted on the outer end of said stub shaft. Supporting means for the pump are shown at 21. The pump 20 is adapted to supply fuel to the atomizing cup to be later described. The inner end of the motor axis has keyed thereto, a disc 23 adapted to drive the atomizing portion. The fuel atomizing means includes a supporting portion 24 positioned in the upper part of the housing 11. A vertical shaft 25 has a bearing 26 in the supporting portion 24, said vertical shaft engaging in a positive manner at its lower end, a drive plate 27, said plate being fashioned in a manner to contain a lubricant therein. A small coil spring 28 provides a tensioned engagement between the drive or rather driven plate 27 and the driving disc 23. A second bearing 29 is shown upon the vertical shaft. Pinned to the upper end of the vertical shaft is a rotary atomizing cup which includes the upper plate 30 flared slightly upward as at 31 at its outer edge. A second cup 32 is disposed thereunder and connected thereto by means of the bolt members 33. A series of wing portions 34 radiating from the vertical shaft 25 lie between the upper plate 30 and the cup 32. The cup 32 is flared similarly to the plate 30 at its outer edges, however, its bottom portion has an aperture 35 therein, said aperture being considerably 110

larger than the vertical shaft, the edges of which are slightly upturned to form a trough 36. A fuel line from the pump 22 discharging into the trough formed by the 5 upturned edges is shown at 38. There is shown at 38^a a control valve for the fuel supply.

An ignition means for the burner is shown 10 projecting through the hearth 10, said ignition means including a housing 39 prohibiting any air blast from extinguishing the gas flame which projects from the jet 40 disposed therein. An ordinary gas pipe connection is shown as 41 and a needle valve 15 mechanism 42 permits regulation of said pilot flame.

The operation of my device is as follows:

I am aware that the prior art discloses vertical shaft burners rotated by an electric 20 motor and having a cup member expelling the fuel mixture in a fan shaped spray. My present burner operates rather similarly to such devices in so far as the supplying of the fuel to the rotating cup and the electric 25 motor is concerned. The rotation of the cup breaks up the fuel and discharges it in a completely atomized spray from between the plate 30 and cup 32. Air is drawn through the aperture 35 in the bottom of the cup in 30 a manner to assist atomization. The bracket 14 and adjustable screw 16 provide means for regulating the speed of the vertical shaft 25 and hence the speed of the atomizing cup.

Oil burners as a rule generally operate at 35 a predetermined speed and the burner structure is assembled with relation to this speed.

It is well known that the fuels utilized by the present so called domestic burners, are very seldom the same, that is with respect to the specific gravity and other manner of grading. Burners of the above type 40 rotating at a single speed, have but one means for controlling the flame, as well as for compensating for the variations in the 45 gravities of fuels utilized, and this means is a needle valve or other equivalent mechanism.

The present device not only contemplates the control of the fuel to the atomizing chamber 50 but also the variation of speed of rotation of the atomizing cup itself. Means is disclosed for moving the drive disc inwardly and outwardly with relation to the driven plate 27 which controls the movement of the 55 vertical shaft and hence the atomizing cup. It is obvious that movement of this driving disc varies the speed of rotation of the atomizing cup, due to the frictional connection.

Applicant by means of his double control 60 namely of fuel and speed of rotation of the cup is adapted not only to burn a greater

variety of fuels but to more efficiently burn them.

What I claim is:

1. In a device of the class described, the 65 combination of a combustion chamber, means for spraying a fuel mixture thereinto, including a rotary atomizing cup, an ignition member, power means, including an electric motor for driving said atomizing cup, a 70 fuel pump, connected to said electric motor, for supplying said atomizing cup in proportion to the speed of the motor, and means for controlling fuel atomization, including an adjustable mechanism for varying the speed 75 of the atomizing cup relative to the speed of the motor.

2. In a device of the class described, in combination, a combustion chamber, means for spraying a fuel mixture thereinto, 80 including a rotary atomizing cup, an ignition member, power means including an electric motor for driving said atomizing cup, a fuel pump connected to said electric motor for supplying said atomizing cup in proportion to the speed of the motor, and means for varying the speed of the atomizing cup relative to the speed of the motor for the purpose of controlling fuel atomizing, 85 including a friction connection between the rotary atomizing cup and the electric motor, and means for varying said friction connection.

3. In a device of the class described, in combination, a combustion chamber, means 90 for spraying a fuel mixture thereinto, including a rotary atomizing cup, an ignition member, power means for driving said atomizing cup, a fuel pump connected to said power means for supplying said atomizing 100 cup in proportion to the speed of the power means, adjustable means for controlling said fuel supply, and means for controlling fuel atomization, including an adjustable mechanism for varying the speed of the atomizing cup relative to the speed of the power means.

4. In a device of the class described, in combination, a combustion chamber, means for spraying a fuel mixture thereinto, 110 including a rotary atomizing cup, an ignition member, power means including an electric motor, for driving said atomizing cup, a fuel pump driven by said electric motor for supplying the atomizing cup, in proportion 115 to the speed of the motor, and means for controlling fuel atomization, including an adjustable mechanism for varying the speed of the atomizing cup relative to the speed of the motor.

In testimony whereof I affix my signature.
JOHN SQUIRES.
